UNITED STATES PATENT OFFICE.

HAROLD JOHN NEWMAN, OF CAVOUR, SOUTH DAKOTA.

ELECTRIC-LIGHT BRACKET.

1,186,428.

Specification of Letters Patent.

Patented June 6, 1916.

Application filed November 12, 1915. Serial No. 61,116.

To all whom it may concern:

Be it known that I, HAROLD J. NEWMAN, a citizen of the United States, residing at Cavour, in the county of Beadle and State 5 of South Dakota, have invented new and useful Improvements in Electric-Light Brackets, of which the following is a specification.

This invention relates to an adjustable 10 lamp bracket and more particularly to a ball and socket bracket, in which means is provided for increasing the frictional contact between the ball members and the socket members for taking up wear and insuring 15 a tight fit between the members for obvious reasons.

The primary object of the invention is to construct a lamp bracket of members through the medium of which the lamp may 20 assume a variety of positions irrespective of the connections between the lamp and the stationary support.

Another object of the invention is to provide simple means for increasing the frictional contact between the ball members and the socket members.

A further object of the invention is to so form the members in duplicate shape that said members can be readily renewed and 30 any slight wear of the contacting surfaces between the socket member and the ball member can be readily taken up by the tightening means hereinafter described.

Other objects of the invention will appear 35 hereinafter, the novel combination of the elements being pointed out in the appended claim.

Referring to the drawings:—Figure 1 is a side elevation of my device showing the 40 same connecting a lamp socket and lamp. Fig. 2 is a longitudinal section showing the coöperation between one ball member and its associated socket member. Fig. 3 is a top plan view of a portion of my invention.

Fig. 4 is a section on line 4—4 of Fig. 1.

Referring to the drawing, the numeral 1 designates any ordinary lamp socket in which is readily mounted the usual electric bulb 2 that receives its current in the usual 50 manner through a cord conductor 3 from an electric lamp plug 4. My invention is interposed between the usual lamp plug 4

and the lamp socket 1. In this particular instance the first ball member of a plurality of ball members 5 is rigidly connected to the 55 lamp plug 4 by means of the shank 6. Inclosing the major portion of each ball member, is a socket member 7 each of which has a rigid connection with the adjacent ball member by means of a shank 7 similar to the 60 heretofore mentioned shank 6, with the exception of the lamp socket member which has a rigid connection by means of a shank 8 with the lamp socket 1.

Each ball member is free to revolve in any 65 direction within the socket member so that the lamp or bulb 2 may assume any position with relation to the lamp plug 4. Each of the socket members is slotted circumferentially as indicated at 9 so as to form a number 70 of fingers 10 alternate ones of which have their free extremities bent at right angles as shown at 11. Attention is called to the fact that previous to bending up the ends of the alternate fingers they have the 75 same length as those fingers that have not their extremities bent up with the result that the band 12 which encircles the fingers is spaced a slight distance from the free ends of the fingers that are not bent. This band 80 12 which encircles all of the fingers is prevented from moving in one direction by means of a bulged portion of the socket member while its movement in the opposite direction is prevented by the angular bent 85 extremities of the fingers, thus it will be seen that when the screw 13 is tightened by pressure being applied thereto, the ends of the band will be drawn together so as to contract the interior area of the socket member 90 which causes the increased friction between the outer surface of the ball member and the interior surface of the socket member for insuring the bulb 2 being retained in any of its adjusted positions.

Obviously various changes could be made in certain parts of the device by one skilled in the art without departing from the spirit and scope of the invention, and for this reason I desire not to be limited to the precise arrangement and constructions of the parts as disclosed.

What I claim and desire to have protected by Letters-Patent of the United States is:—

A lamp bracket comprising a plurality of ball members and a plurality of socket members inclosing said ball members, each of said socket members being slotted at spaced intervals to form fingers the alternate ones of which having right angularly bent extremities and a band encircling the fingers of each socket member to one side of the

center of the latter and abutting the right angularly bent finger extremities.

In testimony whereof I affix my signature in presence of two witnesses.

HAROLD JOHN NEWMAN.
